POLYNITRO ESTERS

Milton B. Frankel, Pasadena, Calif., assignor to Aerojet-General Corporation, Azusa, Calif., a corporation of Ohio

No Drawing. Filed June 20, 1955, Ser. No. 516,794

22 Claims. (Cl. 260—482)

This invention relates to new compositions of matter and a method for their preparation. In particular, it relates to polynitro esters having the general formula:

wherein X is a polynitroalkylene or nitraza-alkylene radical and R and R' are nitroalkyl radicals.

The nitro compounds of this invention are useful as high explosives and can be used in any conventional explosive missile, projectile, rocket, or the like, as the main explosive in powder form into the warhead of the missile, closed in United States Patent No. 2,470,162, issued May 17, 1949. One way of using the high explosives of this invention in a device such as that disclosed in United States Patent No. 2,470,162, is to pack the crystalline explosive in powder form into the warhead of the missile. Alternatively, the crystals can be first pelletized and then packed. A charge thus prepared is sufficiently insensitive to withstand the shock entailed in the ejection of a shell from a gun barrel or from a rocket launching tube under the pressure developed from ignition of a propellant charge, and can be caused to explode on operation of an impact- or time fuse-mechanism firing a detonating explosive such as lead azide or mercury fulminate.

The new compositions of matter of this invention are prepared by condensing nitro acids or acid halides with nitro alcohols, in accordance with the general reaction scheme set forth below:

wherein Z is a hydroxy or halide radical and R, R' and X are as defined above.

As a matter of convenience in obtaining better control and smoothness of the reaction, the reaction is usually conducted in the presence of an inert organic solvent such as ethylene dichloride or chloroform.

To more clearly illustrate this invention, the following examples are presented. It should be understood, however, that these examples are presented merely as a means of illustration and are not intended to limit the scope of the invention in any way.

EXAMPLE I

Preparation of bis(2,2,2-trinitroethyl)-4,7-dinitraza-1,10-decanedioate

In a 100 ml. round-bottom flask, fitted with a condenser and drying tube, was placed a solution of 3.62 gm. (0.02 mole) of 2,2,2-trinitroethanol, in 50 ml. of dry ethylene dichloride. Anhydrous aluminum chloride, 0.27 gm. (0.002 mole), was added and the solution turned yellow. To the solution was added 3.31 gm. (0.01 mole) of 4,7-dinitraza-1,10-decanedioyl chloride. The reaction mixture was refluxed until evolution of hydrogen chloride gas had ceased. The black mixture was cooled and filtered, the solid was washed with cold

dilute hydrochloric acid, water, dried, and recrystallized from ethylene dichloride using charcoal to give 5.3 gm. (85.5%) of white crystals, M.P. 126–128° C. Elemental analysis of the product was as follows:

Calculated for $\text{C}_{12}\text{H}_{16}\text{N}_{10}\text{O}_{20}$: Percent C, 23.23; percent H, 2.60; percent N, 22.58. Found: Percent C, 23.49; percent H, 2.90; percent N, 23.10.

EXAMPLE II

Preparation of bis(2,2,2-trinitroethyl)-4,4,6,6,8,8-hexanitro-1,11-undecanedioate

In a 500 ml. Erlenmeyer flask was placed 100 gm. of 100% sulfuric acid, 18.0 gm. (0.1 mole) of 2,2,2-trinitroethanol, followed by 24.3 gm. (0.05 mole) of 4,4,6,6,8,8-hexanitro-1,11-undecanedioic acid and 50 ml. of chloroform. After standing for five days with occasional shaking, the copious white solid was collected, washed with ice-water, and dried, 35.6 gm. (87.8%), M.P. 114–116° C. Recrystallization from chloroform raised the melting point to 117–118° C. Elemental analysis of the product was as follows:

Calculated for $\text{C}_{15}\text{H}_{16}\text{N}_{12}\text{O}_{28}$: percent C, 22.18; percent H, 1.99; percent N, 20.69. Found: percent C, 22.06; percent H, 1.94; percent N, 20.88.

EXAMPLE III

Preparation of bis(2,2,2-trinitroethyl)-3,6-dinitraza-1,8-octanedioate

In a 500 ml. round-bottom flask, fitted with a condenser and drying tube, was placed 30.3 gm. (0.1 mole) of 3,6-dinitraza-1,8-octanedioyl chloride, 36.2 gm. (0.2 mole) of 2,2,2-trinitroethanol, 300 ml. of ethylene dichloride, and 13.3 gm. (0.1 mole) of anhydrous aluminum chloride. The reaction mixture was refluxed overnight and filtered while warm. The filtrate was evaporated to dryness leaving a brown mushy solid. Trituration with chloroform gave 3.3 gm. of white solid, M.P. 190–192° C. Recrystallization from methyl ethyl ketone-chloroform mixture raised the melting point to 195–197° C. Elemental analysis of the product was as follows:

Calculated for $\text{C}_{10}\text{H}_{12}\text{N}_{10}\text{O}_{20}$: percent C, 20.28; percent H, 2.04; percent N, 23.65. Found: percent C, 20.49; percent H, 2.34; percent N, 23.73.

EXAMPLE IV

Preparation of bis(2,2,2-trinitroethyl)-4,4-dinitro-1,7-heptanedioate

In a 100 ml. round-bottom flask, fitted with a condenser and drying tube, was placed a solution of 3.62 gm. (0.02 mole) of 2,2,2-trinitroethanol, in 50 ml. of dry ethylene dichloride. Anhydrous aluminum chloride, 0.27 gm. (0.002 mole), was added and the solution turned yellow. To the solution was added 2.87 gm. (0.01 mole) of 4,4-dinitro-1,7-heptanedioyl chloride. The reaction mixture was refluxed until evolution of hydrogen chloride gas had ceased. The black mixture was cooled and filtered, the solid was washed with cold dilute hydrochloric acid, water, dried and recrystallized from ethylene dichloride using charcoal to give 2.7 gm. (47.0%) of white crystals, M.P. 170–171° C. Elemental analysis of the product was as follows:

Calculated for $\text{C}_{11}\text{H}_{12}\text{N}_{8}\text{O}_{20}$: percent C, 22.93; percent H, 2.10; percent N, 19.45. Found: percent C, 23.18; percent H, 2.09; percent N, 18.74.

EXAMPLE V

Preparation of bis(2,2,2-trinitroethyl)-4-nitraza-1,7-heptanedioate

In a 100 ml. round-bottom flask, fitted with a condenser and drying tube, was placed a solution of 3.62 gm.

(0.02 mole) of 2,2,2-trinitroethanol, in 50 ml. of chloroform. Anhydrous aluminum chloride, 0.27 gm. (0.002 mole), was added and the solution turned yellow. To the solution was added 2.06 gm. (0.01 mole) of 4-nitro-1,7-heptanedioyl chloride. The reaction mixture was refluxed until evolution of hydrogen chloride gas had ceased. The black mixture was cooled and filtered, the solid was washed with cold dilute hydrochloric acid, water, dried and recrystallized from chloroform using charcoal to give 1.91 gm. (35.9%), of white crystals, M.P. 110-111° C. Elemental analysis of the product was as follows:

Calculated for $C_{10}H_{12}N_8O_{18}$: percent C, 22.56; percent H, 2.27; percent N, 21.05. Found: percent C, 22.58; percent H, 2.26; percent N, 20.93.

EXAMPLE VI

Preparation of bis(2,2,2-trinitroethyl)-3-nitro-1,5-pentanedioate

In a 500 ml. round-bottom flask, fitted with a reflux condenser and drying tube, was placed 10.75 gm. (0.05 mole) of 3-nitro-1,5-pentanedioyl chloride, 18.1 gm. (0.1 mole) of 2,2,2-trinitroethanol, 200 ml. of dry chloroform, and 6.6 gm. (0.05 mole) of anhydrous aluminum chloride. The mixture was refluxed for 1.5 hours, cooled to -20° C., and filtered. The cream-colored solid was washed with cold 6N hydrochloric acid and water, and dried. 19.6 gm. of product were obtained melting at 146-150° C. Recrystallization from ethylene dichloride gave a white crystalline solid, M.P. 160-160.5° C. Elemental analysis of the product was as follows:

Calculated for $C_8H_8N_8O_{18}$: percent C, 19.06; percent H, 1.60; percent N, 22.23. Found: percent C, 19.40; percent H, 2.00; percent N, 22.34.

I have also found that by proceeding in accordance with the method set forth in the above examples, that 4,4-dinitro-1,7-heptanedioic acid condenses with 2,2-dinitropropyl alcohol to produce bis(2,2-dinitropropyl)-4,4-dinitro-1,7-heptanedioate; 4-nitro-1,7-heptanedioic acid condenses with 2,2,2-trinitroethyl alcohol to produce bis(2,2,2-trinitroethyl)-4-nitro-1,7-heptanedioate; and 4-nitro-1,7-heptanedioic acid condenses with 2,2-dinitropropyl alcohol to produce bis(2,2-dinitropropyl)-4-nitro-1,7-heptanedioate.

The dibasic acids used in my invention can be of any

in the practice of my invention are preferably conducted in the presence of $AlCl_3$.

It is apparent from the above discussion that the entire series of polynitro esters, having valuable use as high explosives can be prepared by merely condensing an appropriate nitro acid with a nitro alcohol.

The acids used as starting materials in this invention are obtained by hydrolyzing the corresponding nitriles, as disclosed in assignee's copending application Serial No. 438,296, filed June 21, 1954, now abandoned, or by hydrolyzing their corresponding alkyl esters, as disclosed in assignee's copending applications Serial No. 392,479, filed November 16, 1953, now abandoned, and Serial No. 198,491, filed November 30, 1950, now Patent No. 2,918,489. The acid halides are obtained by reacting the nitro acids with thionyl halide.

I claim:

1. As compositions of matter, polynitro esters having the general formula:

wherein X is a radical selected from the group consisting of polynitroalkylene and nitro-alkylene radicals and R and R' are lower nitroalkyl radicals.

2. As compositions of matter, polynitro esters having the general formula:

where R and R' are lower nitroalkyl radicals, A and A' are lower alkylene radicals and x is a small whole number from 1 to 6 inclusive.

3. As compositions of matter, polynitro esters having the general formula:

wherein R and R' are lower nitroalkyl radicals, A and A' are lower alkylene radicals and x is a small whole number from 1 to 6 inclusive.

4. As a composition of matter, bis(2,2,2-trinitroethyl)-4,7-dinitra-1,10-decanedioate having the structural formula:

5. As a composition of matter, bis(2,2,2-trinitroethyl)-4,4,6,6,8,8-hexanitro-1,11-undecanedioate having the structural formula:

6. As a composition of matter, bis(2,2,2-trinitroethyl)-4,4-dinitro-1,7-heptanedioate having the structural formula:

7. As a composition of matter, bis(2,2,2-trinitroethyl)-4-nitro-1,7-heptanedioate having the structural formula:

chain length desired and can contain any number of gem-dinitro or nitro-alkylene groupings. Thus, such acids as 4,6,8,10-tetranitro-1,13-dioic acid, 4,6,8,10,-

12,14-hexanitro-1,17-dioic acid, 4,4,6,6,8,8-dodecanitro-heptadecane - 1,17-dioic acid, 4,4,6,6,8,8,10,10-octanitro-tridecane-1,13-dioic acid, etc., can also be used in the practice of this invention.

Mixed esters can be produced by employing a mixture of nitro alcohols in the condensation reaction disclosed.

In the preparation of the new compounds of this invention, I have found that the yields obtained are considerably increased when the reactions are conducted in the presence of certain catalysts. Thus it is preferred to conduct reactions utilizing free acids in the presence of 100% sulfuric acid or oleum. Reactions of acid halides

8. As a composition of matter, bis(2,2,2-trinitroethyl)-3,6-dinitraza-1,8-octanedioate having the structural formula:

9. As a composition of matter, bis(2,2,2-trinitroethyl)-3-nitraza-1,5-pentanedioate having the structural formula:

10. As a composition of matter, bis(2,2-dinitropropyl)-4,4-dinitro-1,7-heptanedioate having the structural formula:

11. As a composition of matter, bis(2,2-dinitropropyl)-4-nitraza-1,7-heptanedioate having the structural formula:

12. The method of preparing polynitro esters having the general formula:

which comprises reacting a lower nitroalkanol with a compound having the general formula:

wherein R and R' are lower nitroalkyl radicals, X is a radical selected from the group consisting of polynitroalkylene and nitraza-alkylene radicals and Z is a radical selected from the group consisting of halogen and hydroxy radicals.

13. The method of preparing polynitro esters having the general formula:

which comprises reacting a lower nitroalkanol with an acid having the general formula:

wherein R and R' are lower nitroalkyl radicals and X is a radical selected from the group consisting of polynitroalkylene and nitraza-alkylene radicals in the presence of a catalyst selected from the group consisting of 100% sulfuric acid and oleum.

14. The method of preparing polynitro esters having the general formula:

which comprises reacting a lower nitroalkanol with an acid halide having the general formula:

wherein R and R' are lower nitroalkyl radicals, X is a radical selected from the group consisting of polynitroalkylene and nitraza-alkylene radicals and Z is a halogen radical in the presence of AlCl_3 .

15. The method of preparing bis(2,2,2-trinitroethyl)-4,7-dinitraza-1,10-decanedioate which comprises reacting 2,2,2-trinitroethyl alcohol with 4,7-dinitraza-1,10-decanediol chloride.

16. The method of preparing bis(2,2,2-trinitroethyl)-4,4,6,6,8,8-hexanitro-1,11-undecanedioate which comprises reacting 2,2,2-trinitroethyl alcohol with 4,4,6,6,8,8-hexanitro-1,11-undecanedioic acid.

17. The method of preparing bis(2,2,2-trinitroethyl)-3,6-dinitraza-1,8-octanedioate which comprises reacting 2,2,2-trinitroethyl alcohol with 3,6-dinitraza-1,8-octanediol chloride.

18. The method of preparing bis(2,2,2-trinitroethyl)-4,4-dinitro-1,7-heptanedioate which comprises reacting 2,2,2-trinitroethyl alcohol with 4,4-dinitro-1,7-heptanediol chloride.

19. The method of preparing bis(2,2,2-trinitroethyl)-4-nitraza-1,7-heptanedioate which comprises reacting 2,2,2-trinitroethyl alcohol with 4-nitraza-1,7-heptanediol chloride.

20. The method of preparing bis(2,2-dinitropropyl)-4,4-dinitro-1,7-heptanedioate which comprises reacting 2,2-dinitropropyl alcohol with 4,4-dinitro-1,7-heptanediol chloride.

21. The method of preparing bis(2,2-dinitropropyl)-4-nitraza-1,7-heptanedioate which comprises reacting 2,2-dinitropropyl alcohol with 4-nitraza-1,7-heptanediol chloride.

22. The method of preparing bis(2,2,2-trinitroethyl)-3-nitraza-1,5-pentanedioate which comprises reacting 2,2,2-trinitroethyl alcohol with 3-nitraza-1,5-pentanediol chloride.
